(57) **CLAIM**

The ornamental design for a glucometer screen for checking ketone levels with graphical user interface, as shown and described.

DESCRIPTION

FIG. 1 is a front plan view of a glucometer screen for checking ketone levels with graphical user interface in a first embodiment showing the new design; and,

FIG. 2 is a front plan view of the glucometer screen for checking ketone levels with graphical user interface in a second embodiment.

The broken lines shown in the drawings represent portions of the glucometer screen for checking ketone levels with graphical user interface that forms no part of the claimed design.

1 Claim, 2 Drawing SheetsFIG. 1

FIG. 2
